NECKERCHIEF HOLDER

Edgar W. Ozmon, Minneapolis, Minn.

Application May 13, 1933, Serial No. 671,009

2 Claims. (Cl. 24—49)

This invention relates to a neckerchief holder, and particularly to such a holder of novel structure and of pleasing and attractive appearance. Neckers are now worn by a great many 5 young boys and by certain organizations such as the Boy Scouts, Cubs and Rangers. Boys at the younger ages like to have some insignia on their uniform or costume and a neckerchief holder or ornament forms a very convenient article to 10 carry such an insignia. It is usual for Boy Scouts to be organized in patrols, each of which usually bears some name, such as the name of an animal, Indian tribe, etc. A neckerchief holder can conveniently be constructed to port- 15 tray a representation of the patrol name.

It is an object of this invention, therefore, to provide a neckerchief holder of simple and efficient form which can be easily made from sheet material.

20 It is a further object of the invention to provide a neckerchief holder comprising a piece of sheet material having a picture superimposed upon the front of said piece of sheet material coinciding with said sheet, and said sheet having a loop formed at its rear whereby a neckerchief can be passed through said loop and said holder 25 frictionally held thereon.

It is more specifically an object of the invention to provide a neckerchief holder comprising 30 a piece of sheet material bent to have its front surface somewhat convex about a vertical axis, said sheet preferably having bandlike portions at its lower part which are bent rearwardly and secured together to form a loop, said sheet having 35 a picture imposed on its convex side, the edges of said sheet and said picture coinciding whereby a neckerchief can be passed through said loop and said holder held frictionally thereon with its front side exposed to view.

40 These and other objects and advantages of the invention will be fully set forth in the following description made in connection with the accompanying drawing, in which like reference characters refer to similar parts throughout the 45 several views and in which:—

Fig. 1 is a view in front elevation of the device;

Fig. 2 is a view in side elevation as seen from the right of Fig. 1;

50 Fig. 3 is a developed view or flat view of the blank of sheet material used;

Fig. 4 is a horizontal section taken on line 4—4 of Fig. 1 as indicated by the arrows; and

55 Fig. 5 is a view similar to Fig. 4 showing a modification.

Referring to the drawing, a neckerchief holder is shown, comprising a piece of sheet material 10. While various kinds of sheet material can be used, in practice a sheet of metal or hard sheet fiber have been found suitable. The sheet 10 is formed to coincide with and has superimposed on its front side a picture 11. This picture may also be on sheet material, and while various pictures might be used, in the embodiment of the invention illustrated, a picture of 10 an Indian in full feather dress or headdress is shown. As shown in Figs. 1 and 2, the feathers 11a have substantially pointed ends with pointed spaces therebetween. The sheet 10, as stated, is formed at its edge portions to coincide with the 15 picture so that the sheet 10 underlies the picture 11 at all points but does not project beyond the picture. The sheet 10 when formed as a blank, has at its bottom portion laterally projecting zones or bands 10a. When the device is formed 20 these bands 10a are bent rearwardly in a straight line in overlapping relation as shown at 10b, to form a closed loop 12. The overlapping ends 10b can be secured together by any suitable 25 method, such as by welding or by a suitable adhesive. The sheet 10 and picture 11 thereon, are bent on a comparatively large radius to have a slight concavo-convex form, the front surface being convex about a substantially vertical axis. When the portions 10a are thus bent to form the 30 loop 12, it will be seen as shown in Fig. 1, that the upper portion 10c of the blank 10 extends or projects at one side of the loop 12, the projecting portion as shown in Fig. 1 being formed by the parts constituting the feathers of the headdress in picture 11.

In operation, the neckerchief as usual is folded on a diagonal extending from opposite corners and placed about the neck with the folded corners extending downwardly at the front of the wearer. The strands of the neckerchief are placed through loop 12 extending from top to bottom and the holder is then held frictionally on the neckerchief. The neckerchief is compressed in the loop 12 and the holder can be slid and disposed at the desired point on the neckerchief. The loop 12 is made comparatively flat with its rear side substantially straight, so that there is no wide or thick projection to engage the front of the wearer.

In Fig. 5, the loop 13 is shown in the rear of the sheet 10, which loop is formed from a separate strip or band of material having its rear central portion 13a substantially straight and having its end portions bent and the terminals 13b thereof, secured to the rear of the sheet 10. These ter- 50 55

minals can be secured to the sheet 10 in any suitable manner, as by welding, soldering, or by a suitable adhesive. In the form shown in Fig. 5, sheet 10 and picture 11 will extend in vertical lines 5 at their lower portion, which lines are vertically alined with the end portions of loop 13.

From the above description it is seen that applicant has produced a very simple and efficient structure of neckerchief holder. The device can 10 be easily and inexpensively made from sheet material and at the same time is very attractive in appearance as well as being quite durable. The loop of the device is constructed to be comfortable in wear and the walls thereof will be formed 15 so that there are no edges or portions which chafe the neck. The device is easily and quickly placed in position. The picture 11 can be selected to be of striking color combination and to have a great appeal to younger boys. The device has been 20 amply demonstrated in actual practice and found to be very successful and efficient.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

30 What is claimed is: —

1. An ornament for a neckerchief comprising a piece of sheet material of comparatively high tensile strength bent on a comparatively large radius about a vertical axis to have a convex front

surface, a picture imposed on said convex surface, said piece of material and picture having coincident irregular upper edges, a rigid loop projecting from the rear concave side of said piece and being of oblong shape with its long axis extending transversely of said piece, said loop being of much less height than said picture and said picture extending about the front and side portions of said loop, whereby a neckerchief may be passed through said loop to be held in compressed condition therein so that said ornament will be held frictionally on said neckerchief with said piece having the picture thereon disposed in front of said neckerchief. 5 10

2. A neckerchief holder comprising a piece of sheet material of comparatively high tensile strength bent on a comparatively large radius about a vertical axis so as to have a slightly convex front surface, a second piece of sheet material having a picture thereon with irregular upper and side edges overlying said convex surface and secured thereto, the edges of said sheets being coincident, a rigid closed loop of material of comparatively high tensile strength disposed adjacent the lower edge of said first mentioned piece and 20 projecting from the concave side thereof adjacent the bottom thereof, a portion of which loop is formed by said piece of sheet material, said second piece of material extending about the front and sides of said loop, whereby a neckerchief may be 25 passed through said loop and held in compressed condition therein so that said holder will be frictionally held in place on said neckerchief. 30
